CLAIM

The ornamental design for a bottle, substantially as shown and described.

DESCRIPTION

FIG. 1 is an isometric view of a bottle showing our new design;

FIG. 2 is a front end view of the design of FIG. 1;

FIG. 3 is a rear end view of the design of FIG. 1;

FIG. 4 is a first side view of the design of FIG. 1;

FIG. 5 is a second side view of the design of FIG. 1;

FIG. 6 is a top view of the design of FIG. 1; and,

FIG. 7 is a bottom view of the design of FIG. 1.

The evenly spaced dash-dash broken lines in the drawings illustrate the portions of the bottle that form no part of the claimed design.
